ATTORNEYS.

UNITED STATES PATENT OFFICE.

JOHN B. KLINE, OF CINCINNATI, OHIO.

IMPROVEMENT IN SOFA-BEDSTEADS.

Specification forming part of Letters Patent No. **167,908**, dated September 21, 1875; application filed June 19, 1875.

To whom it may concern:

Be it known that I, JOHN B. KLINE, of Cincinnati, in the county of Hamilton and State of Ohio, have invented a new and Improved Bed-Lounge, of which the following is a specification:

In the accompanying drawing, Figure 1 represents a top view of my improved bed-lounge shown in position as a bed. Fig. 2 is a vertical longitudinal section on the line *c c*, Fig. 1, shown as a lounge, and Fig. 3 is a vertical transverse section of the same on line *xx*, Fig. 2, also in position as bed.

Similar letters of reference indicate corresponding parts.

My invention relates to an improved bed-lounge, that may be readily changed from lounge to bed, and vice versa, having the different parts arranged in a compact, strong, and durable manner; and the invention consists of a main frame with forward-sliding seat-section, and an upward-swinging supplementary section with hinged head-piece that is carried up and adjusted to the level of the seat-section to form the bed therewith.

In the drawing, *A* represents the main frame of my improved bed-lounge, along which the seat-section *B* with its face part is guided, to be slid forward to suitable stoppins *a* at both ends, which prevent the disconnection of frame *A* and section *B*. A supplementary section, *C*, is pivoted to swinging arms *D* of the main frame, and stored below the seat-section *B* when the same is pushed in and used as a lounge, section *C* resting in this position on projecting lugs or pins *b* of frame *A*. The arms *D* are pivoted to frame *A*, and also at both ends and at opposite sides

to section *C*, being guided along raised quadrantal pieces *d*, of such diameter that section *C* may be swung up to a level with the seat-section when the same is drawn out to its full extent. In that position section *C* is locked by a pivoted or spring catch, *e*, at its end, its hinged head-piece *C'* being thrown back on the head-piece of frame *A*, to be supported thereon at the same inclination as the head-piece of seat-section *B*. The lounge is thus changed to a bed, which is quickly returned to its former condition by releasing the catch of the swinging section, lowering the same down on the supporting lugs or pins of frame *A*, and then sliding the seat back to its position on frame *A*. A strong and well-supported lounge or bed is thus obtained, which can be quickly and easily changed from one position to the other.

Having thus described my invention, I claim as new and desire to secure by Letters Patent—

1. A bed-lounge composed of a main frame, *A*, a sliding seat-section, *B*, and of a supplementary section, *C*, with a hinged head-piece, *C'*, arranged within frame *A*, substantially in the manner and for the purpose set forth.

2. The combination of a main frame, having quadrantal side guides and supporting pins or lugs, with a supplementary section swinging on pivoted arms to a level with the drawn-out seat-section, to be locked in this position, substantially in the manner and for the purpose set forth.

JOHN B. KLINE.
